UNITED STATES PATENT OFFICE.

FERDINAND FRÉCHETTE, OF NOTRE-DAME DE CHARNY, QUEBEC, CANADA.

WATER-GRAVE BAR.

Application filed September 1, 1920. Serial No. 407,503.

To all whom it may concern:

Be it known that I, FERDINAND FRÉCHETTE, a subject of the King of Great Britain, residing at Notre-Dame de Charny, Province of Québec, Canada, have invented certain new and useful Improvements in Water-Grate Bars; and I do hereby declare that the following is a full, clear, and exact description of the invention, such as will enable others skilled in the art to which it appertains to make and use the same.

The present invention relates to water grate bars and constitutes an improvement over my previous patents, viz: U. S. A. No. 15 906,521, December 15th, 1908; U. S. A. No. 1,224,159, Mar. 1st, 1917.

The principal object of this invention is to provide a system of hollow grates bars for boilers, furnaces and the like adapted 20 to be connected with a suitable source of water from the boiler supply caused to circulate through said grates and depending pipe system previous to its being discharged into the boiler.

Another object of same is to provide a 25 system of hollow grates bars through which water is caused to circulate for the purpose of obtaining quicker results from the heating, and, reducing the cost of same.

A further and more particular object of 30 this invention is to reduce the cost of combustion of approximately one third, whether wood or coal is used.

A still further object of the invention is 35 to avoid the formation of slag or clinkers on the grates, and, to eliminate any possibility of overheating same, thereby increasing their durability and providing for a system of grates through which the draft 40 is never intercepted and always effective.

Another object of this invention is to provide a system of hollow grates bars through 45 which water is caused to circulate, and by which, should one or more of the said grates become broken, or in any manner become ineffective, the use of the remaining grates bars may be continued, without substantially interfering with the heating capacity of the plant.

With the above and other objects in view 50 which may appear to be inherently related with the scope and nature of this invention, reference is now to be had to the hereunto annexed drawings which are collaterally related with this specification in which the different parts refer to numeral designa-

tions that are identified in the said drawings by similar reference characters.

Of the above mentioned drawings:

Figure 1 is a perspective view of the hollow grates and their connection with the boiler;

Figure 2 is a side elevation of same;

Figure 3 is an end view of same;

Figure 4 is a cross section of a grate bar;

Figure 5 is a side elevation of a clack-valve used with each grate bar;

Figure 6 is a front end view of the grate bar system showing same in two sections;

Figure 7 shows a partial front view of the 70 grate bar head;

Figure 8 shows a side elevation of said grate bar head;

Figure 9 is a side elevation in part section of the entire hollow grates bar system;

Figure 10 is an enlarged longitudinal section of the front part of said system;

Figure 11 is a horizontal section of a separator box shown at the upper part of Figure 9; and,

Figure 12 is a cross section of same.

Now, referring more particularly to the above drawings, in view of fully disclosing the invention thereby illustrated, numeral 85 11 designates a water supply pipe having connection with a boiler 10 and through which, water is supplied to the hollow grates system. This supply of water from the boiler leads its way through said pipe 11 and therefrom descends water return pipe 12 and enters the hollow grates head member 13 at each end of same.

Nipples 14 serve to establish communication between said grates head member and the chambers 15 formed with the extremity of each hollow grates bar 16, by a plug 17 closing the end of same and a clack-valve 18. The water running up through nipple 14 enters chamber 15 and is led through the clack-valve 18 into the elongated space 19 formed with the grates 16, wherefrom it passes through connection 20, at the other end, into the heat absorbing pipes 21 which have their discharge into a separator box 100 22. Once admitted into said separator box, the water falls into a drain 23 formed therewith and again, by gravity, descends a return pipe 24 leading therefrom and which joins in circulation with the water running from pipe 11 into pipe 12 to which said pipe 24 is connected.

The vapor or steam generated throughout the said circulation finds its passage from the separator box 22 where it is collected, into the boiler 10 through the steam pipe 5 connection 25 adapted to establish communication between said separator box and said boiler.

In case of vapor or steam being generated within the grate-head 13, an admission pipe 10 26 leading up therefrom to the separator box 22 is provided for at each end of said grate-head.

Steam generated within the grates 16 closes the valves 18 whereby such steam is 15 shut off from direct flow through pipe 26 to the separator and is forced through admission pipes 20 and 21 in which it is further heated before entering the separator.

20 The grate-head 13, as shown in the drawings, is composed of two sections adapted to be connected together by means of bolts 26' and flanges 27.

This grate-head carries a plurality of 25 valves 28, equal in number to the number of hollow grates connected thereto. The axes of same are in projection with the axes of the nipples 14, providing for the joints between said grate-head and hollow grates.

30 The separator box 22 is also provided with as many valves 29 as there are radiator pipes 21 connected thereto, the valves and pipes being also in alignment.

The said box 22 is so interiorly designed 35 that the water admitted therein through the heat absorbing pipes 21, is maintained in individual sections until it falls in the drain 23 wherefrom it goes back into circulation, passing out again through the outlet 40 pipe 24.

From the above mentioned arrangement of valves 28 and 29, it is obvious that each hollow grate 16, as well as each heat absorbing pipe 21 may be effectively controlled 45 and regulated and even shut off entirely if required.

The water, after having been admitted into the system, will return to the boiler only after having been converted into 50 vapor.

The system, as above referred to and described, will be more efficient and will give a better output than the former ones

claimed in my previous patents. Each grate and radiator being connected separately by a check-valve, not as much vapor will be formed before its discharge into the box 22. The loss of heat is, by the contrivance herein claimed, also substantially avoided from the fact that the outer connections, as 60 disclosed in my previous patents, have all been eliminated.

In the drawings heretofore referred to throughout this description has been shown a certain and preferred form of the invention. It is, however, understood that no limitation is necessarily made to the precise structural details therein exhibited, but, the right is hereby reserved to any changes 65 alterations or modifications to which recourse may be had that come within the scope of the following claims without departing from the spirit of the invention or sacrificing the efficiency of the same.

Having thus fully described my invention, what I claim as new and desire to secure by Letters Patent is:—

1. In combination with a boiler, a separator mounted thereon, a hollow grate head disposed beneath the boiler, hollow grate bars communicating with and extending from said head, admission pipes extending from the bars and the head to the separator, a steam pipe extending from the separator to the boiler, a return water pipe extending 80 from the separator to the grate head, and a water supply pipe extending from the boiler to said return pipe.

2. In combination with a boiler, a separator mounted thereon, a hollow grate head disposed beneath the boiler, hollow grate bars communicating with and extending from said head, admission pipes extending from the bars and the head to the separator, a steam pipe extending from the separator 95 to the boiler, a return water pipe extending from the separator to the grate head, a water supply pipe extending from the boiler to said return pipe, and check valves disposed between said bars and the grate head, 100 said valves being adapted to close by pressure within the grate bars.

In witness whereof I have hereunto set my hand.

FERDINAND FRÉCHETTE.
